UNITED STATES PATENT OFFICE.

BURNS D. LOCKWOOD, OF BELLEVUE, PENNSYLVANIA, ASSIGNOR TO PRERESSED STEEL CAR COMPANY, OF PITTSBURGH, PENNSYLVANIA, A CORPORATION OF NEW JERSEY.

CAR CONSTRUCTION.

1,212,235.

Specification of Letters Patent. Patented Jan. 16, 1917.

Application filed June 1, 1914. Serial No. 842,279.

To all whom it may concern:

Be it known that I, BURNS D. LOCKWOOD, a citizen of the United States of America, residing at 515 Orchard avenue, Bellevue, in the county of Allegheny and State of Pennsylvania, have invented certain new and useful Improvements in Car Construction, of which the following is a specification.

10 My invention relates to railway cars, and has for its object to provide an improved superstructure for cars, the skeleton framing of which can be made entirely of metal, which will be structurally simple, light and 15 strong, which can be manufactured at low cost, and which will also be very compact, so that the car will have a maximum inside width as compared with its outside width.

Another object of the invention is to provide a strong and novel construction of top plate which may extend from end to end or from side to side of the car, and which, when the side posts or end posts are connected thereto, strengthens the superstructure as a whole, and which also serves as a support for the roof plates, or may serve as a support for carlines when a roof having separate transverse members is desired.

A further object of the invention is to 30 provide a novel connection between the side and end top plates of the car.

In the practice of my invention, I contemplate the use of a metallic underframe, such as is used in standard practice, having 35 the usual center and side sills, bolsters and crossbearers, end sills, etc., combined with the construction of my invention to attain the aforementioned objects.

The invention is illustrated, in a preferred embodiment, in the accompanying drawings, wherein:

Figure 1 is a side elevational view of a portion of a box car constructed in accordance with the invention; Fig. 2 is a cross sectional view of a portion of the width of the car taken on the line 2—2 of Fig. 1; Fig. 3 is a side elevational view, on an enlarged scale, of a portion of the side framing of the car; and Fig. 4 is a cross sectional view taken on the line 4—4 of Fig. 3.

Referring more particularly in detail to the drawings, in which like reference characters refer to like parts in the several figures, in which—

55 1 indicates the center sills, 2 the side sills,

3 the bolsters, 4 the crossbearers and 5 the end sills, all of which members may be of any preferred construction.

6 indicates the side top plate which is formed of substantially Y shape in cross section and which extends preferably from end to end of the car. This side top plate preferably comprises parts 7 and 8, which parts are preferably of angular form. The part 7 is provided with an outwardly extending flange 9, a vertical leg portion 10 and an inclined intermediate portion 11, and the part 8 is provided with an inwardly extending flange 12, a vertical leg portion 13 and an intermediate inclined portion 14, 60 which leg portion 13 may be connected with the leg portion 10 of the part 7 by rivets or any other suitable means. When the parts 7 and 8 are secured in the manner just described, the inclined portions 11 and 14 diverge upwardly and are adapted to strengthen and stiffen the side top plate, as a whole, for its full length. To further strengthen and stiffen the side top plate, and to further tie the parts 7 and 8 together, a member 15 is provided which may be connected with the flanges 9 and 12 of the parts 7 and 8. The end top plate 16 65 may be of any suitable form, but as shown in the drawings preferably comprises a member of Z form in cross section, and extends for substantially the full width of the car and may be connected with the side top plate 6 by brackets or angular member 17. This end plate 16 may if preferred 70 also be made of the same construction as that of the side top plate 6.

18 indicates the roof plates which may be secured to the side top plate 6 by rivets or other suitable means, said securing means 75 being also adapted to secure the member 15 to the parts 7 and 8. In the drawings, a roof has been shown which comprises plates 18 having integral carlines, but it will be understood that separate carlines and roof plates may be secured to these side plates. If desired, the member 15 of the side top plate 6 may be dispensed with and the roof plates or carlines secured directly to the flanges 9 and 12 of the side plate. 80

The vertical posts 19, diagonal posts 20 and the end posts 21 may be of any suitable form, but as shown in the drawings are preferably of Z section. To these posts the sheathing 22 of the car is secured. The 85

side posts 19 and 20 extend for substantially the full height of the side wall and at their bottom portions are secured to the side sill 2 and at their top portions are secured to 5 the leg portion of the side top plate 6. The end posts 21 at their bottom portions may be secured to the end sill 5 and at their top portions may be connected with the end plate 16 by members 23.

10 I do not wish to limit the invention to the exact construction shown in the drawings, for it will be apparent to those skilled in the art to which this invention pertains that changes in the details and arrangement of the parts may be made within the 15 spirit and scope of the invention.

Having thus described my invention, what I claim as new and desire to secure by Letters Patent is:

20 1. A car part of Y shape in cross section forming the top member of a load confining wall of the car, a plate extending across said part and a roof resting on said plate.

25 2. A car superstructure construction comprising a plurality of parts, portions of said parts diverging upwardly, a member extending across and connecting said parts and a roof secured to said member.

30 3. A car superstructure part of Y shape in cross section, a plate extending across and connected with said part and a roof resting on said plate.

35 4. A car superstructure part of Y shape in cross section having lateral flanges, a plate extending across said part and secured to said flanges and a roof secured to said plate and flanges.

40 5. A car superstructure part of Y shape in cross section having lateral flanges, a member secured to said flanges, and a roof adapted to rest on and be secured to said member.

45 6. In a railway car, the combination with a Y shaped top plate having lateral flanges, a member secured to said top plate, a member

secured to said flanges and a roof adapted to rest on said member and be secured to said top plate and member.

7. In a car, a superstructure part of Y shape in cross section, a plate extending 50 across and secured to said part, a roof resting on said plate, and means for securing said roof to said part and plate.

8. In a car, the combination with the superstructure, of top plates forming parts 55 of said superstructure, said top plates each comprising a plurality of connected upwardly diverging parts, a member connecting said parts and a roof carried by said plates and members.

9. In a car, a Y shaped superstructure part having lateral flanges, a plate connecting said flanges, a roof and means for securing said roof to said plate and flanges.

10. In a car, a Y shaped top plate having lateral flanges, members connecting said flanges, and a roof resting on said members.

11. A car superstructure part comprising a member having a lower vertical leg portion and upper diverging flanged portions, a 70 member extending across and secured to said flanged portions and a roof resting on said member.

12. A load confining car wall structure comprising a Y shaped top plate, a plurality 75 of posts secured to said top plate, a member extending across said top plate and a roof carried by said plate and member.

13. A load confining car wall structure comprising a Y shaped top plate having 80 lateral flanges, a plurality of posts secured to said top plate, a member secured to said flanges, and a roof secured to said flanges and member.

85 In testimony whereof I affix my signature in presence of two witnesses.

BURNS D. LOCKWOOD.
